UNITED STATES PATENT OFFICE

HARRY L. MYERS, OF TOLEDO, OHIO, ASSIGNOR TO THE AMERICAN FLOOR SURFACING MACHINE COMPANY, OF TOLEDO, OHIO, A CORPORATION OF OHIO

DESIGN FOR A ROTARY DISK EDGING MACHINE

Application filed January 3, 1933. Serial No. 46,684. Term of patent 14 years.

To all whom it may concern:

Be it known that I, HARRY L. MYERS, a citizen of the United States, residing at Toledo, in the county of Lucas and State of Ohio, have invented a new, original, and ornamental Design for a Rotary Disk Edging Machine, of which the following is a specification, reference being had to the accompanying drawings, forming part thereof.

Figure 1 is a front elevational view of a

rotary disk edging machine showing my new design.

Figure 2 is a side elevational view of the machine.

Figure 3 is a rear elevation thereof.

Figure 4 is a top plan view of the same.

I claim:

The ornamental design for a rotary disk edging machine as shown.

HARRY L. MYERS.
